COMMUNICATION SYSTEM

Harry J. Nichols, Binghamton, and Henry L. Tholstrup, Endwell, N. Y., assignors, by direct and mesne assignments, to International Business Machines Corporation, New York, N. Y., a corporation of New York

Application March 26, 1936, Serial No. 70,924

16 Claims. (Cl. 178—35)

This invention relates to communication systems and more particularly to the control of the sending operation of the transmitter in a printing telegraph system or the like.

5 More particularly the invention relates to a printing telegraph system of the synchronous, single impulse type. In a typical system of this character a keyboard is provided at the transmitter, the individual keys of which are associated with segments of a rotary distributor and arranged to control the signal transmission when the distributor makes contact with a segment associated with an operated key. A second rotary distributor is provided at the receiving station 10 which is caused to operate synchronously with that at the sending station, and which is utilized to selectively operate suitable printing apparatus in accordance with the signals sent by the transmitter. It is important in a system of this character that signals be sent to the line in the order in which the keys are depressed and also that all signals sent to the line are of equal length regardless of the length of time a key is held depressed by the operator. It is also important 15 that, should the operator hold the key depressed an unnecessary length of time, only one signal be sent for each key operation, and that no repeat signals be sent.

It will also be apparent that in a certain minor 20 average number of cases a key will be depressed when the rotary distributor is in contact with its associated segment. Under these circumstances, particularly when the key is depressed just as a distributor is about to leave the segment, a casual partial or "clipped" signal will occur. Such clipped signals are a probable source 25 of error. They may fail to actuate line relays, or other signal controlling devices causing a failure or omission of the printing operation; or may delay operation until the receiving distributor has contacted the following segment causing the wrong character to be printed, or causing the printing of two adjacent characters by reason of 30 the operating impulse carrying over from one segment to the next. While the production of clipped signals (where no preventive measure is taken) occurs as a matter of chance, such signals will on the average cause a certain proportion of errors depending upon various characteristics of 35 the telegraph system.

It is accordingly the principal object of the invention therefore to provide a communication system which will assure the sending of proper and uniform signals to the line under all conditions of use.

It is a further object to provide a transmitting apparatus which provides for the sending under all conditions of a single uniform signal to the line regardless of the time when, or the length of time, a key at the transmitter is operated. 5

It is a further object to provide a transmitting apparatus which with a minimum delay in the transmission will effectively avoid the transmission of clipped signals.

It is a still further object to provide a simple 10 and effective signalling method of sending single uniform signals to the line in response to the operation of the transmitter.

Other objects and advantages will be apparent from the following description, the accompanying 15 drawings, and the appended claims.

In the drawings:

Fig. 1 shows in diagrammatic form the elements of one embodiment of the invention as applied to a typical single impulse system, all parts 20 except those relating to the signal sending function being omitted to facilitate the showing and description of the essential features of the invention.

Fig. 2 shows in similar form another embodiment of the invention whereby clipped signals and unintentional repeat signals are suppressed. 25

Fig. 3 shows in similar form a variation in the arrangement shown in Fig. 2, in which the auxiliary relay is energized by the charge stored in 30 a capacitor.

Fig. 4 shows in similar manner another embodiment of the invention as applied to a single impulse system in which the signals are differentiated as to polarity as well as in respect to 35 time, illustrating the method by which clipped signals and repeat signals are prevented.

Fig. 5 is a diagram in similar form showing arrangement of Fig. 4 combined with other control features to provide a complete single impulse transmission system as applied to a typical 40 modern printing telegraph.

Fig. 6 is a diagram showing a modified arrangement for assuring the transmission of proper signals particularly adapted to a system utilizing capacitor or like means in the signal transmission circuit. 45

Referring to Fig. 1, which illustrates particularly the aspect of the invention relating to suppression of partial or "clipped" signals which 50 might occur by chance when a key is depressed at the instant when the rotary contactor has partly traversed the segment operatively associated with that particular key. The elements of the transmitter material to the present descrip- 55

tion comprise a rotary distributor 20, which consists of a series of insulated stationary contact members or segments designated *a*, *b*, etc., two only being shown, these two representing a series 5 corresponding to the keys, *Ka*, *Kb*, etc., of the key board. The distributor also includes a stationary ring 21, and a rotary contactor 22 which connects the segments in proper sequence to the ring. The segments and ring are in practice 10 preferably arranged in concentric circles and are swept over at uniform speed by rotary contactor 22. The distributor elements are shown in linear development in order to simplify the diagram.

The series of sending keys *Ka*, *Kb*, etc., actuated by the operator, are adapted to operate individual key switches *Xa*, *Xb*, etc., by suitable mechanical means, as for example by push rods, but for simplicity the keys and key switches are shown combined. The key switches are preferably of break-make type, the effect of depressing a key being to open the break contacts (top and middle springs) and to close the make contacts (middle and bottom springs). The middle or tongue spring of each key switch is connected 25 directly to its associated segment; the top spring is connected to a common circuit called receive bus 23, and the bottom spring to a common circuit called send bus 26. A pivoted member 15, called the universal bail (shown in cross-section), is mounted transversely underneath all keys in such manner that when any key is depressed, the bail 15 operates auxiliary switch *X* which may be provided with any desired contact combination, in this case a simple make combination being shown. 30 Auxiliary switch *X* cooperates with the key switches and the rotary distributor in controlling an auxiliary relay *XR*, which in turn controls the sending circuits to assure accuracy in transmission of the signals to the line. The source 35 of direct current, which may be a battery, but in accordance with modern practice is preferably a rectifier unit, is indicated at *B*, the negative side being grounded. Resistance *R* represents any type of line coupling device. The connections and circuits will be more fully described in connection with the description of the operations 40 of the arrangement.

The operation of the arrangement shown in Fig. 1 is as follows: Let it be assumed that rotary contactor 22 is sweeping over the distributor in the direction indicated and that key *Kb* has been depressed by the operator just before contactor 22 has reached segment *a*, next in sequence before segment *b*. Simultaneously with the closing of the lower contacts of key switch *Xb*, the contacts 50 55 60 65 70 75 75 of auxiliary switch *X* are closed by universal bail 15, likewise actuated by key *Kb*. When contactor 22 reaches segment *a*, an auxiliary control circuit is completed from positive battery via conductor 19 called the positive bus, ring 21, contactor 22, segment *a*, tongue and upper contacts of key switch *Xa*, receive bus 23, conductor 24, through the winding of *XR*, conductor 25, via contacts 2-3 of switch *X* to ground, thence returning to negative battery. A current pulse through the circuit just traced, termed the auxiliary circuit, energizes relay *XR*, closing contacts 4-5. The characteristics of relay *XR* are such that in the brief intervals when contactor 22 is passing between adjacent segments associated with non-operated keys it will not open its contacts 4-5. Thus when contactor 22 reaches segment *b*, a circuit is established from ring 21, via contactor 22, segment *b*, middle to lower contacts of key switch *Xb*, thence to send bus 26,

conductor 28, through resistor *R* to ground. A current pulse through the circuit just traced, termed the sending circuit, continuing so long as brush 22 contacts segment *b*, produces a voltage across *R*, and hence transmits a corresponding 5 signal impulse to the line. This signal constitutes a full printing signal. When key *Kb* is released, the pressure on universal bail 15 is released, the spring tongue of switch *X* opens its contacts and relay *XR* is deenergized, opening contacts 4-5, 10 thus restoring the circuit to normal condition.

Next let it be assumed that key *Ka* is depressed by the operator at an instant when rotary contactor 22 is in contact with segment *a*. In such event, the tongue and upper contacts of key 15 switch *Xa* are opened and the tongue and lower contacts are closed, connecting the segment to send bus 26. Simultaneously, bail 15 closes contacts 2-3 of auxiliary switch *X*. Thus the auxiliary circuit is incomplete at key switch *Xa*, and 20 the sending circuit being open at contacts 4-5, the transmission of the signal is prevented. However, when rotary contactor 22 reaches a succeeding segment associated with a non-operated key, as for example segment *b*, the auxiliary circuit is closed from ring 21 via contactor 22 to segment *b* via upper contacts of key switch *Xb* to receive bus 23, by conductor 24, winding of relay *XR* and contacts 2-3 of auxiliary switch *X* to ground. Relay *XR* is energized by the current 30 pulse through the auxiliary circuit, closing contacts 4-5, thus completing the sending circuit. Near the end of the revolution, assuming that key *Ka* remains depressed, when contactor 22 again reaches segment *a*, a full signal is sent to 35 the line. Upon the release of key *Ka*, the circuits are restored to normal condition as previously described.

It will be observed that the circuit associated 40 with an operated key is energized upon operation thereof. The corresponding contact segment however is not immediately energized, but becomes energized only after the cooperation of the rotary contactor with a segment corresponding to a non-operated key. In the event a key is 45 depressed at the instant the rotary contactor is in contact with the segment associated with an operated key, the sending of the signal is delayed until the following revolution. Thus partial or 50 "clipped" signals, which would otherwise occur when a key is depressed too late, i. e., when the contactor has already traversed part of the connected segment, are suppressed, and all signals sent to the line are of full length and are properly timed.

Referring now to Fig. 2, the arrangement there shown combines the clipped signal suppressor function of Fig. 1 with a non-repeat function. In Fig. 1, in case the depressed key were held down for more than one revolution of the rotary 60 contactor, a second signal could be transmitted. Such unintentional repeat signals are prevented by the arrangement to be described. The elements of the arrangement are generally similar to those described in connection with Fig. 1. In this arrangement, however, auxiliary switch *X* is provided with three springs forming a break-make combination designated by 1, 2, 3; a capacitor *C* is connected in series with the tongue 2 of switch *X*, and a resistor *R2* in series with the upper 65 spring 1; auxiliary relay *XR* is provided with an additional pair of make springs designated by 6, 7, and with three windings designated by *w1*, *w2*, *w3*. The circuit connections will be made clear 70 in describing the operation.

The operation of the arrangement shown in Fig. 2 in sending is as follows: Assume that key K_b has been depressed, breaking the upper and middle contacts, and closing the middle and lower contacts of key switch X_b , and by means of ball 15, breaking contacts 1-2 and making contacts 2-3 of auxiliary switch X . When contactor 22 reaches segment a (or any segment associated with a non-actuated key), an auxiliary circuit is established from positive battery, conductor 19, ring 21 via contactor 22 to segment a , tongue and upper contacts of switch X_a to receive bus 23, via conductor 24, contacts 3-2 of X , through capacitor C, conductor 24', through winding w_1 of relay XR and conductor 25 to negative battery. A current pulse flows through this circuit, charging capacitor C and energizing relay XR which operates, closing contacts 4-5 and 6-7. These latter contacts apply holding current to relay XR from positive bus 19, contacts 6-7, through windings w_2 and w_1 , via conductor 25 to negative battery. When contactor 22 reaches segment b , the "sending" segment, an impulse is transmitted through the circuit from positive battery, conductor 19, ring 21 via contactor 22, segment b , tongue and lower contact of key switch X_b , to send bus 26, through conductor 27 and winding w_3 , via contacts 4-5 and resistor R to ground. The voltage drop caused by this impulse flowing through resistor R causes the transmission of a signal to the line for the duration of the traverse of contactor 22 across segment b . The current impulse through winding w_3 , which is connected in opposing relation to the other windings, is arranged to neutralize the effect of the holding current in windings w_1 and w_2 ; hence relay XR is de-energized and drops out, opening its holding circuit and contacts 4-5 and 6-7. This arrangement thus provides positive assurance that no more than one signal will be transmitted for any one operation of a key regardless of the length of time the key is depressed. Thus if key K_a remains depressed over a number of revolutions of contactor 22, the contactor closes the circuit above described each time it contacts a segment associated with a non-actuated key. Condenser C remains charged however and hence no substantial current pulse through winding w_1 occurs sufficient to cause actuation of relay XR . Such current flow as may occur is sufficient to maintain the charge on the condenser but insufficient to effect actuation of the relay. The sending circuit therefore remains open at contacts 4-5 and successive repeat signals are not sent to the line in response to contactor 22 closing the sending circuit at the segment corresponding to the actuated key.

This condition prevails until the depressed key is released, permitting contacts 3-2 (of switch X) to open and contacts 2-1 to close. The closing of the latter contacts permits capacitor C to discharge through the circuit containing R_2 , the function of which is to limit the discharge current of C, reducing the tendency of burning or arcing at contacts 1-2. This completes the operating cycle, restoring the circuit to initial condition.

Assuming next that key K_a has been depressed just as contactor 22 reaches, or is on, segment a , then no signal can be sent from segment a , since the sending circuit is open at contacts 4-5 of relay XR . When, however, contactor 22 reaches segment b , the auxiliary circuit is established and relay XR energized as described above, except that the circuit is initially completed from ring 21 via contactor 22 to segment b . The signal impulse is transmitted when contactor 22 again reaches segment a in its next subsequent rotation, in like manner to the transmission via segment b described above. The invention thus provides means assuring that regardless of the time when or the length of time during which a key is depressed, a single proper full signal is sent to the line, and the sending of clipped and non-repeat signals is effectively prevented.

Referring now to Fig. 3, the arrangement shown provides a modified means for securing non-repeat action. In this arrangement a condenser C is connected in a circuit including positive battery and the middle and upper normally closed contacts 2-1 of auxiliary switch X , charging resistor R_2 to ground and negative battery. Thus the condenser is normally charged by battery B.

The operation of this arrangement is as follows: Assume that key K_b has been depressed when contactor 22 is in the position shown. When contactor 22 reaches segment a , or any other segment associated with a non-operated key, an auxiliary circuit is established from conductor 19 connected to the positive side of condenser C, ring 21 via contactor 22 to segment a , via tongue and upper contact of key switch X_a , to receive bus 23, conductor 24 through winding w_1 , conductor 25, via contacts 3-2 of auxiliary switch X to negative side of charged capacitor C. The charge on capacitor C is rapidly discharged through the circuit just traced, quickly energizing relay XR which operates, closing its contacts 4-5 and 6-7. Contacts 4-5 establish the sending circuit, while contacts 6-7 apply holding current to winding w_2 , holding XR in operated condition. The holding current is obtained from one of the sections of battery B, say section B', since a reduced voltage ordinarily suffices to supply the required holding current.

When contactor 22 reaches sending segment b , the signal impulse is transmitted over the sending circuit, which may be traced from positive battery, conductor 19, ring 21 via contactor 22 to segment b via tongue and lower contacts of X_b to send bus 26, thence by conductor 27 through winding w_3 , contacts 4-5 across resistor R to negative battery. The voltage drop across R causes the transmission of a corresponding signal to the line. The local impulse, flowing in winding w_3 in opposition to the current in winding w_2 , sufficiently neutralizes the flux in relay XR that it releases its contact springs which open contacts 4-5 and 6-7. Opening of contacts 4-5 prevents sending of repeat signals to the line. Relay XR can not reoperate, pending the reverse operation of switch X , since its operating energy is derived from capacitor C which was entirely discharged on the first operation of XR . When the depressed key is released, contacts 2-3 of switch X open, and contacts 2-1 close, whereupon capacitor C is immediately recharged from battery B.

Assuming next that key K_a were depressed with contactor 22 in the position shown, or in contact with segment a , no signal can be transmitted inasmuch as the sending circuit is open at contacts 4-5. When contactor 22 reaches segment b , or any other segment associated with a non-operated key, the auxiliary circuit is established, capacitor C discharges through winding w_1 to energize XR as described above, and the sending circuit is established by the closing of

contacts 4-5. When contactor 22 again reaches segment *a*, the local sending impulse flows in the sending circuit, transmitting a signal to the line and de-energizing XR, preventing repeat signals, 5 as explained above. When the depressed key is released, capacitor C is recharged, and the circuits restored to normal condition.

This modified arrangement thus also effectively assures proper sending conditions and provides 10 against the sending of clipped or repeat signals. This arrangement has the further advantage that the energy for operating the auxiliary relay is obtained from the power supply in advance of the transmitting operation and stored in condenser C, and thus does not reduce the voltage 15 of the current source when needed for generating the signal impulse even though the operation of relay XR occurs immediately prior to the sending of the signal. This promotes uniformity 20 in the amplitude of the transmitted signals. An ample quantity of energy for operating the auxiliary relay may be stored in capacitor C, and when required may be very quickly discharged through the relay winding, producing very rapid 25 action.

Referring now to Fig. 4, the arrangement there shown is an embodiment of the invention as applied to a single impulse system in which the signals are differentiated as to polarity as well as 30 in respect to time. The distributor 20 is in this case provided with two series of segments preferably grouped in pairs, the arrangement being such that one series of segments transmits signals of one polarity to the line, while the other 35 series transmits signals of opposite polarity. The sending circuit is shown as being coup'ed to the line by resistors R and R' whose junction is grounded, but other line coupling arrangements may be used as desired. Two sending and two 40 receiving busses are provided, being numbered 26, 26' and 23, 23' respectively. Signals sent via send bus 26 may be regarded as having positive polarity, and those sent via send bus 26' as having negative polarity. Rotary contactor 22 contacts 45 a pair of segments simultaneously, but since only one key of a pair is depressed at the same time, only one signal is transmitted. Auxiliary relay XR is provided with contacts 4 to 11, the purpose of which will be hereinafter described. Auxiliary switch X is provided with bail 15 which 50 is adapted to be operated simultaneously with the operation of any of the keys.

The operation in transmission is as follows:— Assume that key Kc is depressed just as contactor 22 reaches paired segments *a*, *b*, or any 55 other pair of segments associated with non-operated keys, closing the tongue of key switch Xc to the lower contact. Bail 15 simultaneously closes the tongue of auxiliary switch X to the lower contact. An auxiliary control circuit is set 60 up from positive battery via contacts 1-8 of relay XR, conductor 23', upper contacts of key switch Xb, segment *b*, via contactor 22 to segment *a*, via upper contacts of key switch Xa to send bus 23, conductor 24, via contacts 11-10, 65 through winding w1, conductor 34, through capacitor C, lower contacts of switch X to ground. The current pulse through this circuit energizes relay XR and charges condenser C. Upon operation, relay XR opens contacts 7-8, 10-11, 70 and closes contacts 4-5, 6-7, 8-10. Contacts 6-7 apply positive current via conductor 19 to ring 21, contacts 9-10 apply holding current to winding w1 via a circuit including conductor 34, 75 resistor R3, lower contacts of switch X to ground.

Contacts 4-5 establish the sending circuit. Resistor R3 is made of relatively high value so that it passes only sufficient current to hold relay XR operated but not enough current to cause relay XR to pull in when de-energized.

When contactor 22 reaches segment *c*, the sending circuit is completed as follows: From positive battery, contacts 6-7, conductor 19, ring 21 via contactor 22 to segment *c*, via lower contacts of Xc to send bus 26, via conductor 27, 10 through winding w3 via contacts 4-5, conductor 28, resistor R to ground. The current impulse through the circuit traced sends a positive signal to the line, and acting through opposing winding w3 neutralizes the flux in relay XR which 15 drops out, opening the contacts closed when it operated. Resistor R3 being of high value, only a small leakage of the charge on capacitor occurs, and this charge is continually replenished each time contactor 22 contacts a pair of segments associated with non-operated keys. The 20 charging current flowing at any one time in the auxiliary circuit under these circumstances is very small and insufficient to cause relay XR to pull in.

Relay XR thus remains unoperated until the depressed key is released, permitting capacitor C to be discharged through the upper contacts of switch X and discharge resistor R2, thus providing non-repeat action. If it is assumed that 30 key Kd were depressed, rather than key Kc, under the conditions stated above the analysis would be the same, except that the signal impulse is sent via segment *d*, key switch Xd, send bus 26', conductor 27' and resistor R1 to ground, causing a negative polarity signal to be sent to the line.

Assuming next that key Ka is depressed when contactor 22 is traversing segment *a*, it will be evident from the foregoing analysis that the auxiliary control circuit will be open at key switch Xa, hence relay XR will not be operated, its contacts 4-5 are open, and consequently a signal cannot be transmitted until the next revolution of contactor 22. In case key Kb is depressed when contactor 22 is in contact with segment *b*, and the auxiliary circuit will be open at key switch Xb, and the operation of relay XR cannot occur until a succeeding segment associated with a non-operated key is contacted and the signal cannot be sent to the line until the next revolution of contactor 22. It will therefore be evident 45 that the transmission of proper uniform signals is assured and the transmission of clipped signals and repeat signals is effectively prevented.

Referring now to Fig. 5, the arrangement there shown illustrates an embodiment of the invention as applied to a single impulse system in which the signals are differentiated with respect to polarity as well as to time, with key board control and interlock means. The distributor 20 is provided with two series of segments grouped in pairs as described in connection with Fig. 4. Four keys and associated apparatus are shown, these being representative of a complete key 60 board for transmitting letters and signs in the well known manner of the typewriter. All key levers are preferably at the same level, their outer ends projecting in a uniform row in such manner that all keys are capable of operating universal 65 bail 15 and can be controlled by latch means presently to be described. The latch is actuated by latch magnet LM shown in operative relation to latch bar 30 which is pivotally mounted on the frame of the machine, and is provided with a 70 75

- turned edge or hook so formed and positioned as to hook over the end of a key lever in the depressed position, and underneath the ends of all levers in the normal position. Thus when latch 5 30 is in the engaged position, it latches the depressed key in the depressed position, but prevents the depression of any other key until the latch moves out of engagement (see dotted line position of latch associated with key K_a). Auxiliary relay XR is provided with three windings w_1, w_2, w_3 and with contact 4 to 12, the purpose of which will become clear in the description of the operation.
- The operation in transmission is as follows: A 10 capacitor C is arranged to be normally maintained in charged condition by means of a circuit including positive battery, normally closed contacts 7-8 of relay XR , condenser C , normally closed middle and upper contacts of auxiliary switch X , and charging resistor R_2 to ground. Assuming that key K_c has been depressed as 15 shown, when contactor 22 reaches segments a, b , (segments associated with a non-operated key) an auxiliary circuit is established from positive side of condenser C , via conductor 33 to receive bus 23', tongue and upper contact of key switch X_6 to segment b , via contactor 22 to segment a , via tongue and upper contact of key switch X_a to receive bus 23, by conductor 24 through winding w_1 and conductor 34, and via lower and middle contacts of auxiliary switch X to negative side of charged capacitor C which now discharges through the circuit traced. A current pulse through this circuit energizes relay XR which 20 operates, opening contacts 7-8 and closing contacts 4-5, 6-7, 9-10, 11-12. Contacts 4-5, 11-12 establish the sending circuits; contacts 6-7 apply positive battery to ring 21 through winding w_3 ; contacts 9-10 apply holding current to winding w_2 , and operating current to latch magnet LM through a circuit including battery B , conductor 35, winding w_2 , conductor 36, winding LM , conductor 37, contacts 9-10 to frame and thence returning to negative battery. 25 Magnet LM is shown connected in series with winding w_2 , but may be connected in parallel therewith if desired. Magnet LM actuates latch 30 which latches down the depressed key and locks all other keys in the normal unoperated 35 position. The latch action is sufficiently rapid that the operator need not make any conscious effort to hold the depressed key down, but can merely strike the key as in ordinary typing.
- When contactor 22 reaches sending segment c , 40 the sending circuit is completed from ring 21 via contactor 22 to segment c , thence via lower contacts of key switch X_c to send bus 26, via conductor 27, contacts 11-12, conductor 28, through resistor R to frame and thence returning to negative battery. The voltage drop appearing across resistor R due to the local current impulse in 45 the circuit just traced sends a signal of positive polarity to the line. The current impulse through winding w_3 produces a flux counter to that of winding w_2 , de-energizing relay XR and releasing the contact springs which return to normal position as shown. This breaks the sending circuit at contacts 4-5 and 11-12, hence repeat signals cannot be sent to the line. Re-operation 50 of XR is prevented by the lack of charge on capacitor C which was discharged at the beginning of the sending cycle. Potential is removed from ring 21 when contacts 6-7 open. Contacts 9-10 open the circuit supplying current to winding w_2 55 and to latch magnet LM , de-energizing same and

releasing latch 30, which is restored to un-operated position by retractile spring 31, thus releasing the depressed key. As the released key returns to normal position under the influence of a suitable spring means, the tongue of auxiliary switch X shifts to the upper contact, permitting battery B to charge capacitor C through resistor R_2 , thus restoring all circuits to initial normal condition.

Assuming next that contactor 22 is on segment c when key K_c is depressed, the associated key switch X_a has its tongue depressed so that the auxiliary circuit upon which operating winding w_1 of relay XR depends for operating current is open, and hence the sending circuit is not 10 established until the pair of segments next in sequence are contacted. It will thus be apparent without further detailed analysis that the section of the auxiliary circuit between receiving busses 26' and 26 will be interrupted when any key 15 is depressed when in contact with contactor 22; the circuit may only be closed and signals transmitted following the actuation of a key when contactor 22 first contacts a pair of segments 20 other than those associated with the operated key. Hence provision is made for sending full length signals of the proper characters and clipped signals are effectively prevented.

The operation of the system is substantially 25 the same for every other key. Thus for example 30 when key K_d is operated, an auxiliary circuit is established when contactor reaches a pair of segments associated with a non-operated key such as segments a, b , including positive side capacitor C , upper contacts of key switches X_a and X_b , and through winding w_1 of relay XR as described above. Relay XR is energized, connects in its own holding circuit, energizes latching magnet LM and establishes the sending circuit through its contacts 4-5, so that when contactor 22 35 reaches segment d , a sending pulse or signal is sent to the line. The circuit for this pulse is from positive battery, contacts 6-7, winding w_3 , ring 21, via contactor 22 to tongue and lower contact of key switch X_d , via send bus 26', conductor 27', contacts 4-5, conductor 28', through resistor R_1 to frame and negative. The voltage drop across resistor R_1 is in the opposite 40 direction to that occurring when key K_c is depressed, and sends a signal of negative polarity 45 to the line. The remainder of the operation is the same as described above for the operation of key K_c . Thus assurance is provided for the proper transmission of signals of desired characteristics upon the operation of any of the keys 50 of the machine.

It should be noted that upon depressing a key, the operated key is latched down, and all unoperated keys are locked against possible depression until after the signal is transmitted, hence 55 the signals are perforce sent in the order in which the keys are depressed. The key latch also holds the operated key down until the signal is sent, even though the operator merely strikes the key and releases it. In case the key is held too long, 60 unintentional repeat signals are not transmitted.

It thus becomes clear that the invention, in a simple and practical manner, assures the satisfactory transmission of proper signals without attention by the operator. The method and apparatus disclosed permits the operator to transmit easily and accurately merely by observing a reasonable cadence within the speed limitations 65 of the system.

Referring now to the modification of Fig. 6, 70 75

there is shown an embodiment of the invention as applied to a transmitting arrangement in which the printing signals are initiated by the discharge of individual capacitors associated with the sending keys, each key K_a , K_b , etc., is provided with an individual capacitor C_a , C_b , etc., connected in such manner that upon depression of a key the capacitor is charged from the battery B , and upon the release of the key, the capacitor is discharged to initiate the sending of a signal. An auxiliary relay XR is provided to control the sending circuit as in prior embodiments. The resistor R represents any line coupling means and may be a relay, transformer, or other suitable device. The distributor is provided with one or more pairs of special segments p' , p'' with which the rotary contactor 22 contacts to complete the auxiliary control circuit, although a separate distributor or other suitable alternative means may be employed. A universal bail 15 , operated in common by the sending keys as in prior examples, actuates the auxiliary switch X . The circuit connections will be traced in describing the operation.

The operation is as follows: Assume that key K_a is depressed, then with the key in the depressed position, capacitor C_a is charged from positive bus 19 via the tongue and lower contact of the associated key switch K_a , through capacitor C_a to negative bus 29 . Simultaneously, universal bail 15 is pushed down by key K_a and closes the lower contacts of auxiliary switch X , charging capacitor C . Upon release of key K_a , retractile means (not shown) moves the key to close the upper contacts of the key switch, and at the same time the upper contacts of auxiliary switch X are permitted to close. When rotary contactor 22 reaches segment a , no signal is sent because the sending circuit is open at contacts $4-5$ of relay XR . When rotary contactor 22 contacts the paired segments p' , a circuit is set up from negative bus 29 via capacitor C , via upper contacts of auxiliary switch X , conductor 24 , via paired contacts p' , by conductor 26 through winding w_1 of relay XR to negative bus 29 . Capacitor C discharges through the circuit just traced, energizing relay XR which closes contacts $4-5$, thus establishing the sending circuit. Holding current for relay XR is furnished through resistor R_2 , which is made of such value that the current is sufficient to hold relay XR in operated position, but is not sufficient to operate the relay in the absence of the operating current provided by capacitor C . When contactor 22 again reaches segment a , capacitor C_a discharges through the circuit including the upper contacts of key switch K_a , from segment a via contactor 22 to ring 21 , by conductor 27 , contacts $4-5$ and through opposing winding w_2 of relay XR , through resistor R , to negative bus 29 . The current pulse caused by the discharge of capacitor C_a through this circuit produces a voltage across resistor R sending a signal to the line. The current through opposing winding w_2 energizes relay XR , which releases to permit contacts $4-5$ to open, thus opening the sending circuit and preventing unintentional repeat signals.

Since the auxiliary control circuit must be completed by means of segments not included in the sending circuit, casual partial or mutilated signals are prevented in the event contactor 22 is in contact with a segment associated with the sending key at the instant of release of the key. Assuming that key K_a is closed at the

instant when the contactor 22 is just beyond paired segments p' , it will be seen that when contactor 22 makes contact with segment a , the sending circuit will not be closed, hence another revolution of the rotary contactor will be required in order to transmit the signal. Such delay in transmission may be reduced by providing the distributor with a plurality of paired auxiliary contacts connected in parallel with contacts p' as indicated for example by contacts p'' .

It will be observed that the circuit arrangement and procedure are somewhat different than in previous examples, but that the same general principles are followed.

While the methods herein described, and the forms of apparatus for carrying these methods into effect, constitute preferred embodiments of the invention, it is to be understood that the invention is not limited to these precise methods and forms of apparatus, and that changes may be made in either without departing from the scope of the invention which is defined in the appended claims.

What is claimed is:

1. A communication system of the character described comprising a plurality of operable members, means for transmitting timed impulses of certain time duration upon the operation of each of said members, and means providing for the transmission of a complete impulse for every operation of said members, including means controlled by said members, irrespective of the time of operation of said members, to effect transmission of impulses of equal time duration.

2. A communication system of the character described comprising a plurality of individual circuits, periodic means sequentially cooperating with said circuits to condition each said circuit for transmitting conditions, means for energizing said circuits selectively to cause the transmission of a signal impulse upon cooperation of said periodic means with the particular circuit energized, and means controlled by the second mentioned means to delay the energization of certain of said circuits at certain times to prevent the transmission of a partial signal impulse.

3. A communication system of the character described comprising a plurality of different circuits, periodic means sequentially cooperating with said circuits, means for energizing said circuits to cause the transmission of a signal impulse upon cooperation of said periodic means with the particular circuit energized, and means controlled by the second mentioned means to delay the transmission of an impulse when any of said circuits is energized during the time that said periodic means is in cooperative relationship with that circuit.

4. A communication system of the character described comprising a plurality of different circuits, periodic means sequentially cooperating with said circuits, means for energizing said circuits to cause the transmission of a signal impulse upon cooperation of said periodic means with the particular circuit energized, and means controlled by the second mentioned means to suppress the transmission of an impulse in response to energization of one of said circuits unless energization of said circuit has been completed prior to the cooperation of said periodic means with that circuit.

5. In a communication system of the character described, a plurality of operable keys, means for transmitting a timed signal impulse of distinc-

- tive characteristics upon the operation of each of the several keys, and means controlled by the first mentioned means to suppress the transmission of a signal impulse upon operation of each of the said keys at certain times to prevent the transmission of a partial signal impulse.
6. A communication system of the character described comprising a plurality of operable keys, circuits associated respectively with said keys adapted to be conditioned upon operation of each of said keys, means cooperating with each of said circuits sequentially to transmit a timed signal upon cooperation thereof with a conditioned circuit, and means controlled by the said keys to delay the transmission of the signals in the event that the particular circuits are not conditioned prior to the cooperation of the said means therewith.
7. In a communication system of the character described, a plurality of circuits, means to condition said circuits, a transmission circuit, periodic means cooperating with said plurality of circuits sequentially to energize the transmission circuit upon cooperation with the conditioned circuits, means to delay the energization of said transmission circuit in the event that the circuits are not conditioned prior to cooperation of the said periodic means therewith, and means controlled by the said first mentioned means so as to operate upon the conditioning of any one of said first mentioned circuits to prevent the conditioning of any other of the said first mentioned circuits until the energization of the said transmission circuit has been effected.
8. In a communication system of the character described a plurality of operable members, circuits associated respectively with said members adapted to be conditioned upon operation of each of said members, a transmission circuit, periodic means cooperating with said first mentioned circuits sequentially to energize the transmission circuit upon cooperation with the conditioned circuits, means to delay the energization of said transmission circuit in the event that the circuits are not conditioned prior to cooperation of the said periodic means therewith, and means to maintain the circuits associated with said operated members conditioned until the energization of the transmission circuit is effected.
9. In a communication system of the character described a plurality of operable members, circuits associated respectively with said members adapted to be conditioned upon operation of each of said members, a transmission circuit, periodic means cooperating with said plurality of circuits sequentially to energize the transmission circuit upon cooperation with the conditioned circuits, means to delay the energization of the transmission circuit in the event that the said circuits are not conditioned prior to cooperation of the said periodic means therewith, means to maintain the circuits associated with the said operated members conditioned until the energization of the transmission circuit is effected, and means operated upon the operation of said member to prevent operation of the others of said members until after the energization of the transmission circuit is effected.
10. A communication system of the character described comprising a plurality of operable members, circuits associated with the members adapted to be energized upon the operation thereof, a plurality of contacts corresponding to said circuits, a movable member periodically engaging said contacts in sequence, means for transmitting a signal in response to engagement of said member with an energized contact, and means controlled by said operable members for energizing the contact corresponding to an energized circuit only when said member is in engagement with a contact corresponding to a non-energized circuit.
11. A communication system of the character described which comprises a plurality of operable members, periodically moving means having a cooperative sequential relation with said members, means providing for the transmission of a signal of timed characteristics upon the cooperation of said moving means with an operated member, and means controlled by the operable members effecting a delay in the transmission of said signal until a succeeding cooperative relation when operation of said member occurs during the existence of a cooperative relation between said means and said member.
12. A communication system of the character described which comprises a plurality of operable members, periodically moving means having a cooperative sequential relation with said members, means providing for the transmission of a signal of timed characteristics upon the cooperation of said moving means with an operated member, and means controlled by said members to delay the transmission of a signal until the moving means has first established cooperative relation with a non-operated member.
13. A communication system of the character described comprising, in combination, a plurality of control circuits, periodic means to cooperate with said circuits sequentially, a transmission circuit, means to condition the control circuits to effect energization of the transmission circuit upon cooperation of the periodic means with the conditioned circuits, and means controlled by the second mentioned means to maintain the transmission circuit deenergized in the event that the control circuits are not conditioned prior to the cooperation of the periodic means therewith.
14. A communication system of the character described comprising, in combination, a control circuit, means to condition said circuit, a transmission circuit to transmit signal impulses, periodic means cooperating with said circuit to energize said transmission circuit upon cooperation with the conditioned circuit, and means controlled by the first mentioned means controlling the transmission circuit to maintain it deenergized upon the transmission of the signal irrespective of the number of times said periodic means cooperates with the conditioned circuit.
15. A communication system of the character described comprising, in combination, a plurality of operable members, circuits associated with members and adapted to be conditioned upon operation of the corresponding members, a circuit for the transmission of signal impulses, periodic means cooperating with said circuits sequentially to energize the transmission circuit upon cooperation with a conditioned circuit, and means controlled by said members to maintain the transmission circuit deenergized thereafter irrespective of the length of time the member remains operated to condition the associated circuit thereby limiting the transmission of the signals to one for each conditioned circuit.
16. A communication system of the character described comprising, in combination, a plurality of operable members, circuits associated with said members and adapted to be conditioned upon op-

eration of the corresponding members, a circuit for the transmission of signal impulses, periodic means cooperating with the said circuits sequentially to energize the transmission circuit upon cooperation with a conditioned circuit, means to maintain the transmission circuit deenergized after transmitting a signal irrespective of the

length of time the said member is operated and the associated circuit remains conditioned and means controlled by said members to prevent the operation of others of said members until the transmission of the said signal.
